R. H. LAWSON

METHOD OF AND MEANS FOR INSERTING FASTENINGS

Filed Feb. 11, 1924

UNITED STATES PATENT OFFICE.

ROBERT H. LAWSON, OF BEVERLY, MASSACHUSETTS, ASSIGNOR TO UNITED SHOE MACHINERY CORPORATION, OF PATERSON, NEW JERSEY, A CORPORATION OF NEW JERSEY.

METHOD OF AND MEANS FOR INSERTING FASTENINGS.

Application filed February 11, 1924 Serial No. 692,054.

My invention relates to the insertion of fastenings, particularly for the purpose of attaching heels to shoes, as by nailing through the heel-seat of a shoe into a heel.

5 In work of the character just indicated, commonly termed "inside nailing", it is necessary to drive the heel-attaching nails as close to the periphery of the heel as possible to obtain a tight rand-crease. Yet, the nails 10 thus driven must not be so close to the crease as to emerge through the side walls of the heel or to come into the field of action of the breasting and edge-trimming tools. Also, in the inside nailing of heels, in which the nails 15 may not be driven through and clinched, but may have their points within the heel-substance, it becomes desirable to so drive said nails as to increase their resistance to withdrawal. It is therefore an object of my in- 20 vention to provide for the insertion of the nails in a manner attaining these results.

In the accomplishment of this object, a feature of the invention consists in positioning a nail or other fastening preparatory to insertion, and then forming it, as by swaging an inclined surface upon its entering end, to determine the direction it shall take. In the attachment of heels to shoes, this direction is with reference to the periphery of the heel, 25 the nails being operated upon to cause them preferably to follow paths away from such periphery. The nails may thus be driven in close proximity to the rand-crease without danger of coming outside the wall of the finished heel. At the same time, the courses of the nails so depart from straight lines that they are strongly held by the heel-substance. To obtain the closeness of the nails to the 30 rand-crease, this being without regard to the manner in which their direction of insertion is governed, I may independently determine the points of insertion of the attaching series by the form of the work, as the counter-portion of the shoe which is to be heeled. As 35 herein disclosed, this locating of the nails is accomplished after the formation of their points, they being held against rotation to prevent disturbance of the predetermined direction of insertion. In connection with 40 heels provided with openings, their relation to the inserting mechanism may be determined by positioning means entering such openings.

A particular embodiment of the machine

of my invention is illustrated in the accompanying drawing,

Fig. 1 being a front elevation of a heel- 55 er to which the present improvements are applied and which is organized to carry out the herein-disclosed method;

Fig. 2, a central vertical section through the work-support or jack of this machine;

Fig. 3, a perspective view of the upper portion of the jack;

Fig. 4, a similar view of the gang of swag- 60 ing tools;

Figs. 5 and 6, enlarged vertical sectional details through one of the nail-tubes, showing the elements, respectively, in the nail-receiving and swaging positions; and

Fig. 7, a perspective view of a nail engaged by the retaining member and particularly illustrating the formation of its point.

In many respects, the apparatus of this invention may be similar to that disclosed in 75 Patent No. 446,885, Pope, February 24, 1891. There is illustrated a frame 10, at the upper portion of which is carried a horizontal block 12, this, in the present instance, serving only as an abutment against which the work is 80 pressed during the nailing operation. Arranged to reciprocate vertically in the frame 10 are side rods 14, 14, connected at their lower extremities by a cross-head 16 and at their upper ends by a top girt 18. In the 85 present machine, this top girt is without function, save to tie the side rods together. The cross-head and side rods, in their reciprocation, supply power for the various operations of the machine, being driven by an eccentric rod 20 pivoted to the cross-head and surrounding an eccentric 22 fixed upon a main shaft 24 rotatable in the frame.

In opposite ways 26, adjacent to the side rods, a slide 28 is movable vertically, this 95 slide being provided with horizontal ways 30. Arranged to travel along the ways 30, from a position clear of the block 12, at which it is accessible by the operator, to one beneath said block, this being the operating position, 100 is a jack-base 32 carrying at its upper end a jack 34. As in the machine of the patent already referred to, the jack-slide may be raised and lowered with reference to the block 12 by screw mechanism 36 and cam mechanism 38. This latter mechanism includes a slide 39, the elevation and depression of which by the associated cams commun-

cates movement to the jack. The screw mechanism 36 is actuated by a rack and pinion 40 and lever 42 from a treadle 44, while the cam mechanism acts as a result of the reciprocation of the side rods, being connected to these at 46.

Guided to oscillate toward and from the longitudinal axis of the jack in vertical depressions 48 surrounding its periphery are nail-tubes 50, pivoted at 52 by cylindrical extensions arranged to turn in horizontal grooves in the jack and permitting some lateral bodily movement of the tubes, as well as their oscillation. The opposite sides of the tubes are flat, contacting with the adjacent walls of the depressions to furnish bearings which guide the tubes in their movement. Through each tube is a vertical nail-holding bore, with its receiving opening 54 in an end surface of the tube situated just below a surface 56 of the jack upon which the heel-seat of a shoe is supported during the nailing operation. Just above the pivotal point of each nail-tube is formed a cam-slot 58 inclined upwardly and inwardly, each of these slots having operating in it a roll 60 rotatable upon a horizontal extension from an actuating rod 62. Each rod is mounted to reciprocate vertically in the outer portion of the base 32, there being one of these corresponding to each of the nail-tubes 50. Movable within the base is a sleeve or operating member 64 having horizontal bores to receive shanks 66 of connecting collars 68, one of these collars surrounding each of the rods 62. Within a bore in each collar is a friction plug 70, the outer end of which is held by a spring 72 against a flattened portion 74 of the corresponding actuating rod 62. Formed upon the outside of the sleeve is a vertical rack 76, with which meshes a pinion 78 journaled in the base and provided upon the forward extremity of its spindle with a hand-wheel 80, by which the pinion may be rotated to raise and lower the sleeve. As illustrated in Fig. 2 of the drawing, the sleeve 64 is in its lowest position, holding the rolls 60 at the bottom of the cam-slots 58, the nail-tubes being thereby maintained in their inmost positions in the depressions 48. This latter relation is best shown in Fig. 3. When the hand-wheel 80 is rotated to raise the sleeve, the friction plugs bearing against the surfaces 74 of the actuating rods carry the rolls upward along the cam-slots, swinging the nail-tubes out until they are arrested by the contact of their upper extremities with the inner surface of the counter-portion of a shoe, as that illustrated at S in Fig. 2. This brings each nail-receiving opening 54, independently of the associated tubes, close to the rand-crease, to insure a uniformly tight joint about the entire crease. Upon contact between the tubes and shoe, the frictional connections between the plugs and rods slip, so that further rotation of

the hand-wheel is without effect upon the tubes, each of which has been brought to its bearing against the counter without interference with its companions. Opposite rotation of the hand-wheel lowers the sleeve 64 and the rods, drawing the rolls down the cam-slots and returning the nail-tubes to their normal positions. Here again the frictional connections may slip when the tubes are seated in their depressions.

Having a bearing within the base 32 above the sleeve 64 is a plunger 82 provided with a central shank 84 passing downwardly through the sleeve. Mounted to oscillate freely about ball-and-socket joints 86 are holders 88 for drivers 90 operating in the nail-tubes. These drivers may be positioned manually through a rack 92 carried at one side of the lower extremity of the shank 84 and engaged by a pinion 94. The spindle of the pinion is journaled in the base 32, and has fast upon its forward extremity a hand-wheel 96, by which it may be rotated to raise and lower the plunger 82. The drivers may be operated under power by contact of a plunger 100 with the extremity of the shank 84. This plunger is carried by a bell-crank-lever 102 fulcrumed upon the slide 28 carrying the jack. A link 104 joins the lever 102 to a bell-crank-lever 106 pivoted on the cam mechanism slide 39, the lever 106, at its opposite extremity from the link 104, being united by a link 108 to the cross-head 16. Consequently, when this cross-head reciprocates, the oscillation of the lever-system raises the plungers 100 and 82, and therefore the drivers, the travel of the latter being sufficient to bring the nail-engaging ends of the drivers to the tops of the tubes 50, to effect the insertion of the nails N. The weight of the connecting elements, especially the plungers, may be sufficient to return the drivers to their lowered position when the cross-head 16 is brought to normal by its eccentric.

When supported in the tubes 50 upon the drivers 90, the upper extremities or points of the nails N may be formed by a gang of swaging tools 110. Each of these tools may consist of a rod having an inclined pressure-face 112 and depending from a plate 114. The plate is mounted to turn about one of the side rods 14, from an inactive position, as is illustrated in Fig. 1, until it contacts with a stop 116 upon the block 12, at which time one of the tools 112 is aligned with each of the openings 54 and acts longitudinally of a tube 50 containing a nail, the point of which is to be formed. The nails being supported upon the ends of the drivers, which are so located vertically by manipulation of the hand-wheel 96 that the nail-points are just below the openings 54, the operator, by depressing the treadle 44, raises the jack by the screw mechanism 36, to force the nails against the faces 112 of the tools, as is illustrated in Fig.

6 of the drawing. This forms upon each nail a surface inclined oppositely to the swaging face of the tool. The angle at which each face is situated about the axis of the tool is 5 such as to produce a surface upon the nail, the pressure upon which in driving will cause a deflection of the entering point of the nail in the desired direction. For the purposes of the present invention, the swaging faces, 10 when co-operating with the openings 54, are inclined upwardly and inwardly from the periphery of the jack, so that the nails N, in driving, follow paths curved away from the periphery of the heel which they attach. It 15 is to be observed, that the formation of the nails takes place while they are positioned for insertion. It is therefore unnecessary to give further attention to the angular relation of their points, but merely to hold them 20 against rotation about their axes.

To retain the nails with their points in the proper angular positions after swaging, each tube 50 is slotted at its inner side just below the opening 54, and has pivoted in it at 118 25 a retaining finger 120. This finger has an enlarged contact-end 122, grooved vertically at 124 to partially embrace the nail and thus give such frictional engagement as will hold said nail against accidental rotation about 30 its axis. The contact-end of the finger is forced normally toward the nail by a spring 126 extending between the lower extremity of the finger and an adjacent portion of the nail-tube. Upon the outer side of each finger, 35 between its contact-end and pivot, is a projection 128, which, at the time the nail is to be retained, lies in a reduced portion 130 of the driver. This reduced portion or groove extends for a sufficient distance along the driver 40 to provide for the retaining engagement of the finger with the nail at all times during its forming and driving. The groove, however, stops short of the upper end of the driver, leaving a portion of full diameter at 131, 45 against which the projection 128 rests when the driver is in the position for loading the nail into the nail-tube. This carries the end 122 away from the nail-receiving bore, leaving this free for the entrance of the nail.

To permit a heel H to be correctly assembled with the shoe S for attachment, both shoe and heel are preferably provided with openings, two of these being illustrated at s 50 in the heel-seat, spaced along the longitudinal axis of the shoe, and corresponding openings h in the heel. These openings are so formed in the heel-seat and heel, that when they are in alinement the periphery of the heel is properly related to the exterior of the 55 counter-portion of the shoe for the attachment of the former. To facilitate the gaging operation, the jack 34 has two pins or projections 132 extending upwardly from the surface 56, these pins entering first the openings s in the heel-seat, when the shoe is jacked,

and then the openings h in the heel, when this latter is placed upon the heel-seat. By this means, the correct relation of the shoe to the jack, as well as the heel to the heel-seat of the shoe, is assured. To permit the pins to 70 accommodate themselves to heel-openings of different depths, they may be yieldably mounted in the jack, being backed by springs 134, against which they may be depressed upon the application of pressure to their 75 upper extremities.

To outline generally the carrying out of my improved method by this machine, it may be said that with the elements in the relation illustrated in Fig. 1 of the drawing and the 80 jack drawn out from beneath the block 12, nails are supplied to the openings 54 of the tubes 50. At this time, the drivers are as illustrated in Fig. 5, the fingers 120 being forced back by the portions 131 of the drivers to 85 clear the tubes for the reception of the nails. Now the operator, by turning the hand-wheel 96, raises the drivers until the points of the 90 nails reach the height illustrated in Fig. 6, at which time each finger-projection 128 enters the depression 130, releasing its finger 120 to cause the engagement and retention of the nail against rotation by the portion 122. Thereupon, the plate 114 may be swung 95 against the stop 116, so that the tools 110 are in registration with the openings 54 and the treadle 44 depressed. This, through the screw mechanism 36, elevates the jack, and the pressure of the nail-points against the surfaces 112 of the tools swages over said points to the 100 form illustrated for one of the nails in dotted lines at n in Fig. 7. The formation of the entering extremities of the nails being completed, the jack is lowered and drawn out, the 105 swaging tools moved to their inactive position, and a shoe-upper S, in the heel-seat of which have been formed the gage-openings s, s, is placed upon the jack with the heel-seat-portion resting upon the surface 56 over the openings 54. Rotation of the hand-wheel 80 by the operator then carries out the upper 110 ends of the nail-tubes, under the influence of the movement of the sleeve 64 communicated through the frictional connections and cam-slots, until each tube is stopped in the nailing 115 position by its contact with the counter-portion of the shoe adjacent to the rand-crease. The heel H may then be applied to the heel-seat of the shoe, gaged in relation thereto by the entrance of the pins 132 into its openings h, h. The operator slides the jack in beneath the block 12, and depresses the treadle 44 to apply preliminary pressure to the work, the heel being raised into contact with the under 120 side of the block and forced against the heel-seat. Actuating the usual starting lever 136 trips the clutch of the machine, and final pressure is applied for the nailing operation by the action of the cam mechanism 38, this 125 being followed by the elevation of the drivers 130

under the influence of the plunger 82 actuated from the slide 16. As the swaged points of the nails enter the substance of the heel, the horizontal component of the resistance to their movement deflects them inwardly away from the periphery of the heel, so they are caused to follow the paths indicated in Fig. 2, and at the same time, by their departure from right lines, to set up a considerably greater resistance to displacement than would be present if they were driven straight into the heel. At the end of the cycle of operation of the machine under power, the drivers resume the position appearing in Fig. 5, the work is relieved from pressure, and the jack may be drawn out for the removal of the heeled shoe and the performance of the succeeding operation.

Having described my invention, what I claim as new and desire to secure by Letters Patent of the United States is:—

1. The method of inserting fastenings, which consists in positioning a fastening preparatory to insertion, forming the fastening while thus fixed in position to determine the direction of insertion, and effecting the insertion of the fastening from the forming position.

2. The method of inserting fastenings, which consists in placing a fastening in a position preparing it for a direct movement of insertion, forming the thus positioned fastening to determine the direction of insertion, retaining the formed fastening against disturbance in the forming position to prevent disturbance of the predetermined direction of insertion, and effecting the insertion of the formed fastening.

3. The method of inserting fastenings, which consists in fixing in position a fastening preparatory to insertion, forming upon the entering end of the fastening a surface inclined to the axis of said fastening to cause its pressure against the work during insertion to deflect it from the direction of said axis, and effecting the insertion of the fastening in a direction determined substantially from its forming position by such inclination of the entering end.

4. The method of attaching heels to shoes, which consists in positioning a securing device for co-operation with a heel and heel-seat of a shoe, forming the entering end of the securing device in a predetermined relation to the periphery of the heel, and forcing the securing device in such relation into the work.

5. The method of securing objects by nails, which consists in positioning the nails for co-operation with the objects, swaging to inclined form the entering ends of the nails while thus positioned, and driving the nails into the objects after the completion of their formation.

6. The method of attaching heels to shoes by inside nailing, which consists in supplying

nails to a jack, changing the form of the nails to cause them to follow paths away from the periphery of the heel to be attached, jacking a shoe, applying a heel to the jacked shoe, and driving nails through the heel-seat of the shoe into the heel.

7. The method of attaching heels to shoes by inside nailing, which consists in supplying nails to a jack, performing an operation upon the nails to cause them to follow paths away from the periphery of the heel to be attached, jacking a shoe, applying a heel to the jacked shoe, moving the nails after the operation upon them into positions determined by the form of the counter-portion of the jacked shoe, and driving nails through the heel-seat of the shoe into the heel.

8. The method of attaching heels to shoes by inside nailing, which consists in supplying nails to a jack, forming upon the entering ends of the thus-supplied nails inclined surfaces having predetermined relations to the periphery of the jack, holding the formed nails against rotation, jacking a shoe, applying a heel to the jacked shoe, and driving nails through the heel-seat of the shoe into the heel.

9. The method of attaching heels by inside nailing, which consists in supplying nails to a jack, jacking a shoe, holding each of the series of nails at points independently determined by the form of the shoe, applying a heel to the jacked shoe, and driving the nails through the heel-seat of the shoe into the heel.

10. In a machine for inserting fastenings, means for holding a loose fastening preparatory to insertion, means for forming the fastening thus held, and means for inserting the formed fastening.

11. In a machine for inserting fastenings, a tube arranged to receive a fastening, a driver operating in the tube, and fastening-forming means acting longitudinally of the tube.

12. In a machine for inserting fastenings, a tube, a driver, and means for determining the direction of insertion of the fastenings co-operating with opposite extremities of the tube.

13. In a machine for inserting fastenings, a tube arranged to receive a fastening, a driver operating in the tube, and fastening-retaining means co-operating with the tube and forming means acting upon the retained fastening.

14. In a machine for inserting fastenings, means for holding a fastening for insertion, a swaging tool arranged to act upon the entering end of the fastening thus held against movement, and means for inserting the swaged fastening.

15. In a machine for inserting fastenings, means for holding a series of fastenings for insertion, a gang of swaging tools arranged

- to act simultaneously upon the entering ends of the fastenings thus held against movement, and drivers for contact with the swaged fastenings.
- 5 16. In a heel-attaching machine, nail-holding means, drivers co-operating therewith, and forming means co-operating with the holding means and arranged to produce inclined surfaces upon the points of the nails in a predetermined relation to the periphery of the heel to be attached.
- 10 17. In a heel-attaching machine, nail-holding means, drivers co-operating therewith, forming means co-operating with the holding means and arranged to produce inclined surfaces upon the points of the nails in a predetermined relation to the periphery of the heel to be attached, and retaining members contacting with the nails during the operation of the forming means and drivers.
- 15 18. In a machine for inserting fastenings in shoes, a shoe-support having a series of fastening-inserting mechanisms movable thereon, and means arranged to move the mechanisms simultaneously to a point for each mechanism determined independently of the associated mechanisms by contact with the supported shoe.
- 20 19. In a shoe-nailing machine, a jack, a plurality of nail-inserting mechanisms movable thereon, means arranged to move the mechanisms simultaneously, and frictional connections between the moving means and each inserting mechanism, said frictional connections being arranged to permit movement of the inserting mechanisms independently of one another.
- 25 20. In a shoe-nailing machine, a jack, a plurality of movable nail-tubes pivoted upon the jack, an actuating member co-operating with each tube, an operating member common to the actuating members, and frictional connections between the operating and actuating members, said frictional connections being arranged to permit movement of the actuating members independently of one another.
- 30 21. In a fastening-inserting machine, a shoe-support having depressions opening through its periphery, and nail-tubes movable toward and from one another through the openings of the depressions to points determined by a shoe on the support.
- 35 22. In a heel-attaching machine, a jack, nail-tubes pivoted thereon and having cam-surfaces, and movable members arranged to actuate the nail-tubes and contacting with the cam-surfaces.
- 40 23. In a heel-attaching machine, a jack, nail-tubes pivoted thereon and having cam-surfaces, movable members arranged to actuate the nail-tubes and contacting with the cam-surfaces, and a member common to the actuating members and arranged to move them simultaneously.
- 45 24. In a heel-attaching machine, a jack, nail-tubes pivoted thereon and having cam-surfaces, rods arranged to reciprocate upon the jack, a sleeve movable upon the jack, and frictional connections between the sleeve and rods.
- 50 25. In a machine for inserting fastenings, a fastening-receiving tube, a driver movable in the tube between positions in which the fastening is received in the tube and in which the insertion is completed, and a retaining member arranged to act upon the fastening in the tube, the driver co-operating with the retaining member in the fastening-receiving position to render said retaining member ineffective.
- 55 26. In a machine for inserting fastenings, a fastening-receiving tube, a driver movable in the tube, and a member having a portion arranged to contact with the fastening in the tube and retain it in position for insertion and an independent portion for contact with the driver.
- 60 27. In a machine for inserting fastenings, a fastening-receiving tube, a driver movable in the tube, and a retaining member having a portion for contact with the fastening in the tube and an independent portion for contact with the driver, there being a depression in the driver to receive the last-mentioned portion.
- 65 28. In a heel-attaching machine, a jack, a nail-tube movable upon the jack toward and from its longitudinal axis, a driver operating in the tube, and a member pivoted upon the tube and having a portion for contact with a nail therein.
- 70 29. In a heel-attaching machine, a jack, a nail-tube movable upon the jack, a driver operating in the tube, and a member pivoted upon the tube and having an end-portion arranged to contact with a nail in the tube and a portion intermediate such end-portion and the pivot and arranged for contact with the driver.
- 75 30. In a heel-attaching machine, a jack, a nail-tube movable upon the jack, a driver operating in the tube, and a member pivoted upon the tube and having an end-portion arranged to contact with a nail in the tube and a portion intermediate such end-portion and the pivot and arranged for contact with the driver, the driver being provided with a depression to receive the intermediate portion.
- 80 31. In a machine for inserting fastenings, a fastening-receiving tube, a driver movable therein, fastening-forming means co-operating with the tube and driver, and means arranged to move the driver to a fastening-receiving position and a fastening-forming position, and temporarily retain it in each position, and means for moving the driver to a fastener-inserting position.
- 85 32. In a machine for inserting fastenings in heels provided with openings, fastening-inserting mechanism including movable tubes
- 90 95 100 105 110 115 120 125 130

- arranged to receive the fastenings and inserting means movable within the tubes, and means arranged to enter the heel-openings to position a heel with relation to the inserting mechanism. 5
33. In a heel-attaching machine, a jack having movable nail-tubes and co-operating heel-positioning means, and nail-drivers movable in the tubes. 10
34. In a heel-attaching machine, a jack having movable nail-tubes terminating in proximity to its heel-seat-portion and heel-positioning means situated on such heel-seat-portion between the extremities of the tubes, and nail-drivers movable in the tubes. 15
35. In a machine for attaching a heel provided with positioning openings, a jack having nail-tubes terminating in proximity to its heel-seat-portion and projections from such heel-seat-portion arranged to enter the heel-openings, and nail-drivers movable in the tubes. 20
36. The method of attaching heels by inside nailing, which consists in supplying nails to a jack, jacking a shoe, positioning each of 25
- the supplied nails at points determined independently of the associated nails under the influence of the jacked shoe, applying a heel to the shoe, and driving the nails through the heel-seat of the shoe into the heel. 30
37. In a fastening-inserting machine, a shoe-support, a plurality of fastening-inserting mechanisms movable upon the support, and means arranged to move the fastening-inserting mechanisms through different distances outward into contact with the supported shoe. 35
38. In a heel-attaching machine, a jack, a plurality of nail-tubes movable upon the jack, and means for forcing the tubes toward the counter-portion of a jacked shoe. 40
39. In a heel-attaching machine, a jack, a plurality of nail-tubes movable upon the jack, drivers operating in the tubes, and means for successively moving the tubes through distances determined by the jacked shoe and for operating the drivers. 45

In testimony whereof I have signed my name to this specification.

ROBERT H. LAWSON.
